Joseph Soss.

Joseph Soss,
By his Attorney, Edgar Gale Esq.

UNITED STATES PATENT OFFICE.

JOSEPH SOSS, OF NEW YORK, N. Y.

HINGE-BUTT.

1,109,876.

Specification of Letters Patent. Patented Sept. 8, 1914.

Application filed April 9, 1914. Serial No. 830,622.

To all whom it may concern:

Be it known that I, JOSEPH Soss, a citizen of the United States, and residing at New York, in the county of New York and State of New York, have invented certain new and useful Improvements in Hinge-Butts and Methods of Making the Same, of which the following is a specification, such as will enable those skilled in the art to which it applies to make and use the same.

This invention relates to hinge butts and particularly to the butts of, or separate parts of, what are known as invisible hinges wherein one butt or part thereof fits in and is movable in the other butt or a part thereof; and the invention consists of an improvement in hinge butts of this class and in the method of making the same, whereby a hinge butt or butts of the class specified consists of a part formed from thin metal inclosed, or partially inclosed, in a casting of metal, or a composition of metals, whereby a hinge butt of said form may be completely finished in a mold, thus avoiding all machining, finishing, dressing, or the like, and whereby a portion of one butt or part will fit snugly in and work freely and smoothly in the other butt or part.

The invention is fully disclosed in the following specification, of which the accompanying drawing forms a part, in which the separate parts of my improvement are designated by suitable reference characters in each of the views, and in which;—

Figure 1 is a sectional view showing a mold which I employ and showing a complete section of a hinge butt involving my invention, the section being on the line 1—1 of Fig. 5; Fig. 2 a similar view of the hinge butt detached or removed from the mold; Fig. 3 a view similar to Fig. 2, but showing both parts of a hinge connected; Fig. 4 a partial section on the line 4—4 of Fig. 5; Fig. 5 a view of the hinge butt shown in Fig. 2, and looking in the direction of the arrow 5, and; Fig. 6 a view similar to Fig. 5, but showing only a yoke-shaped or box-shaped core or frame member used in the construction of my improved hinge butt.

In Fig. 3 of the accompanying drawing, I have shown a complete hinge comprising a butt or part *a* and a butt or part *b*. The butt or part *b* consists of a plate *b*² adapted to be secured to a door post, frame, or other stationary member, in the usual manner, and said plate is provided with a curved arm

*b*³ which is pivoted in a yoke-shaped or box-shaped member *c* fitted into and detachably secured in a corresponding yoke-shaped or box-shaped part *a*² of the hinge butt or member *a*, all these parts, in the main, being of the usual and well known construction and forming no part of my invention which consists of the butt *a* and the method of making the same.

In carrying my invention into effect, or in making the hinge butt *a*, I provide a yoke-shaped or box-shaped core or frame member *a*³ of thin or sheet metal, said part *a*³ being preferably stamped from sheet steel, and the side portions thereof are provided with oppositely directed wing members *a*⁴ in the outer end portions of which are formed screw holes *a*⁵, and in the inner end portions of which are formed other screw holes *a*⁶, as clearly shown in Fig. 6, and as partially shown in Figs. 1, 2, 3 and 4. I also provide a mold *d* consisting of a female member *e* and a male member *f*, and the female member *e* is provided with a chamber *e*² of the same general form as the body portion of the yoke-shaped or box-shaped frame member *a*³ and is adapted to receive the same, and in the face of said female member are oppositely directed recesses *e*³ adapted to receive the wing portions *a*⁴ of said frame member, and the inner parts *e*⁴ of which are of greater depth than the outer parts.

The male member *f* of the mold is provided with a central plunger *f*² of less dimensions than the chamber *e*² but of the same form and adapted to enter said chamber, and the face portion of the metal member *f* is also provided with oppositely arranged recesses *f*³ which correspond with the recesses *e*³ and have raised portions *f*⁴ adapted to form in the face of the wing portions of the complete hinge butt *a*, recesses *a*⁷ to receive the oppositely directed wing portions *c*² of the part *c* which is detachably secured in the hinge butt *a*, in the operation of forming a complete hinge, as shown in Fig. 3. The male member *f* is also provided with pin plungers *f*⁵ which correspond with the screw holes *a*⁵ in the wing portions of the frame member *a*³, and with other pin plungers *f*⁶ which correspond with the screw holes *a*⁶ in said frame member, and the pin plungers *f*⁶ are preferably larger than the pin plungers *f*⁵.

In the operation of forming the complete

hinge butt *a*, the mold members *e* and *f* are secured together, after which the molten metal, or a composition of metals in a molten condition is forced into the mold 5 through an aperture or apertures *g*, or in the usual or any preferred way; and this molten metal, with the construction shown, will entirely inclose all parts of the frame member *a*³. With the construction shown, 10 the body of the frame member *a*³ would have only a thin coating of the cast metal on the outer side thereof, as shown at *h* in Fig. 2, and on the inner side thereof would be a corresponding thin coating *h*² except at the 15 sides *h*³, which said coating is preferably thicker, while the wing portions of said butt *a* would be provided on both sides with thick heavy coatings of cast metal, as shown at *h*⁴.

20 In the above described operation, the pin plungers *f*³ of the part *a*⁴ of the mold, form screw holes *i* in the hinge butt *a* which are afterward threaded to receive the screws *i*² which secure the parts *c* to the butt 25 *a* in the operation of forming the complete hinge, and the pin plungers *f*⁵ form larger screw holes *i*³ through which are passed other screws used in securing the hinge butt *a* to a door or other swinging device. The 30 screw holes *i* formed by the pin plungers *f*³ and the screw holes *i*³ formed by the pin plungers *f*⁵ are of less dimensions than the corresponding screw holes in the wing portions *a*⁴ of the frame member *a*³ of the butt 35 *a*, and with this construction, the cast metal through which the screws are passed incloses said screws and aids in binding the inner and outer parts of the castings of the wing portions of the hinge butt *a* together, as 40 clearly shown in Fig. 3, and as indicated in Fig. 2.

With my improvement, the hinge butt *a* is exactly and accurately finished in the operation of casting or molding, as herein described, and the yoke-shaped or box-shaped 45 part of the butt *a* will exactly and snugly re-

ceive the part *c* of the hinge butt *b* which is independently formed, without any machining or other finishing of said butt *a*, and the butt *a* may thus be made, completed, and finished much more economically and expeditiously than when cast or otherwise formed as a hole, and afterward finished and bored and recessed to receive the screws by which said butt is secured to a swinging 5 door or other device, and the screws *i*² which secure the part *c* of the butt *b* in the butt *a* and the recesses *a*⁷ which receive the part *c*² of said butt *b*.

It must be understood that the form of 60 the hinge butt *a* as herein shown and described and the method of using the same are old, and my invention is not limited to the particular form of the butt *a* herein claimed and described, nor to the formation 65 of a hinge butt designed for use as a part of an invisible hinge, and my said improvement may be utilized in the construction of hinge butts of different styles, shapes, or forms, and designed for use in connection with, or 70 as a part of hinges of other shapes, forms, or designs.

Having fully described my invention, what I claim as new and desire to secure by Letters Patent is:—

1. A hinge butt, comprising an inner core or frame member of sheet metal inclosed and reinforced partially or wholly by a casting or castings. 75
2. A hinge butt, comprising a yoke-shaped or box-shaped frame member of sheet metal and having side wings, said parts being inclosed and reinforced by a metal casting or castings. 80

In testimony that I claim the foregoing 85 as my invention I have signed my name in presence of the subscribing witnesses this 4th day of April 1914.

JOSEPH SOSS.
